UNITED STATES PATENT OFFICE.

JULIEN GUENIFFET AND JULES NICHAULT, OF PARIS, FRANCE.

DEVICE FOR ROLLING TIPS FOR CIGARETTE-MACHINES.

No. 848,647.

Specification of Letters Patent.

Patented April 2, 1907.

Application filed December 28, 1905. Serial No. 293,074.

To all whom it may concern:

Be it known that we, JULIEN GUENIFFET and JULES NICHAULT, both citizens of the Republic of France, and both residing at Paris, France, have jointly invented certain new and useful Improvements in Devices for Rolling Tips for Cigarette-Machines, of which the following is a specification.

This invention relates to a device for rolling tips for cigarette-machines.

In the said device the strip of paper to be rolled is caught by an intermittently-rotating spindle having a split end to receive the point of the strip. The latter is clamped between the branches of the spindle by the action of any suitable mechanism—such, for instance, as a socket slidable on the spindle—in such a manner that the split end of the spindle will be caused to bulge out a little and that the socket will have to bear on the said bulged part when slid thereon. The end of the said socket is conical, so as to enable it to become readily disconnected from the tip on the latter being wound in part around the same and in part around the split spindle. When the socket or other mechanism leaves the branches of the spindle, the said branches spring away from each other, so that the tip is enabled to be thrown readily away afterward from the spindle by an ejecting-ring slidable on the said socket and on the spindle.

One embodiment of this invention is shown, by way of example, in the accompanying drawings.

Figure 1 is a longitudinal vertical section of the device in the position when the point of the strip of paper has just been caught by the branches of the split spindle. Fig. 2 is a partial plan view corresponding to Fig. 1. Fig. 3 is a central longitudinal section of a portion of Fig. 1 enlarged. Fig. 4 is an end elevation of the spindle and the members surrounding the same.

In the drawings, 1 designates a spindle co-acting with a larger rod 2, which carries a slidable sleeve 3, serving to impart an intermittent rotation to the same. For that purpose the sleeve 3 has on its opposite sides clutch members 4 and 5, capable of engaging now with a clutch-sleeve 6, secured to the main frame 7, and then with a clutch-sleeve 8, which receives from a shaft 9 a continuous rotary motion through the toothed wheels 10 and a pinion 11, loosely mounted on the rod 2. The engagement of the clutches is

shifted by means of a swinging lever 12, which takes into the hollow end of the sleeve 3 and is actuated by a cam 13.

The spindle 1 is surrounded by a slidable 60 socket 14, to which is secured a tube 15, provided with collars 16. A lever 17, actuated by a cam 18 of the shaft 9, is engaged between the collars 16, and thus reciprocates the tube 15 and the socket 14. 65

The end of the spindle 1 is so slit as to be provided with two branches 19, which when free move slightly away from each other and have their middle slightly bulged out beyond the extended cylindrical surface of the body 70 of the spindle, so that they are caused to approach each other when the socket 14 is slid thereon and to clamp the point of the strip of paper 20, of trapezium shape, engaged between the said branches. 75

The outer surface of the end of the socket is slightly conical and the socket terminates in a thin bevel, so as to form a surface nearly continuous with that of the end of the spindle when slid thereon, as shown in the 80 drawings, in order that the triangular part of the strip of paper 20 shall be suitably wound in part on the spindle and in part on the socket 14.

At the rear part of the tube 15 there is 85 formed a slideway or race, into which takes a pin 22 of the rod 2, so that the tube 15 and the socket 14 turn at the same time as the spindle, while being enabled to slide. Around the socket 14 is located a movable ejecting- 90 ring 23, having a lateral rib whereby it is connected to any suitable controlling mechanism (not shown) in such a manner as to be slidable on the socket.

The device is mounted in a main frame 25, 95 to which is secured a sleeve 26, having a flared lateral slit 27 to be entered by the strip of paper 20, and an opposite slit, in which the rib 24 is slidable. The bore of the said sleeve comprises a cylindrical part 28, in 100 which the ring 23 is slidable, and a larger cylindrical part 29, in which the tube 15 is slidable.

The operation is as follows: The spindle being at rest, its slit is placed in front of the 105 slit 27 of the sleeve 26 and the socket 14 is moved back, so that the branches 19 will spring open. A strip 20 is then inserted in the slit 27 and up between the branches 19. The socket is pushed into the position shown 110 in the drawings, so as to nip the branches 19 onto the strip 20. Then the sleeve 3 is

clutched with the revolving sleeve 8, so that rotary motion is imparted to the spindle, which winds the strip of paper around its end and around the socket 14 to form a tip within 5 the sleeve 26, until the sleeve 3 is brought back against the fixed sleeve 6 and stops the spindle. The socket is again moved back, so that its conical part will withdraw from the tip and at the same time allow the branches 10 19 to spring back. Finally, the ring 23 is so moved as to throw the tip out of the sleeve 26, after which it is moved back to its position of rest.

Instead of the slidable socket 14 any other 15 suitable device may be used to cause the branches of the slit spindle to nip onto the point of the strip of paper to be wound.

The controlling mechanisms hereinbefore described may of course be replaced by any 20 other equivalent mechanisms.

What we claim is—

1. In a cigarette-machine, an apparatus for winding or rolling comprising a slit spindle having a bulged part, and a socket movable along the said spindle, the end of the 25 said socket which engages the bulged part of the spindle having an outer conical surface adapted to form a conical surface substantially continuous with the end of the spindle 30 when the socket is brought into position to close the slit.

2. In a cigarette-machine, an apparatus for winding or rolling comprising a rotary slit spindle, a socket slidable on the said 35 spindle to close the slit portion, and slidable connections to cause the said socket to turn or revolve with the spindle.

3. In a cigarette-machine, an apparatus for rolling or winding a tapered strip to form a mouthpiece with a spiral loose within it for 40 preventing escape of the tobacco and substantially cylindrical on the outside, including in combination a spindle with means at its end for catching the point of such strip, said spindle having a substantially conical 45 surface on which said strip is wound, and a sleeve having a cylindrical bore surrounding said conical surface.

4. In a cigarette-machine, an apparatus for rolling or winding comprising a slit spindle, means for closing the said slit to catch a sheet of paper inserted in the slit, and an ejecting-ring surrounding said spindle and reciprocable relatively thereto.

5. In a cigarette-machine, an apparatus 55 for rolling or winding a tapered strip, including in combination a slit spindle 1, a socket 14 sliding over said spindle and adapted when slid forward to close said slit to catch in its end the point of said strip inserted in the slit, 60 and a sleeve 26 surrounding said spindle and having a flared slit through which the paper may be introduced to the slit of the spindle.

In witness whereof we have hereunto signed our names in the presence of two sub- 65 scribing witnesses.
